Attorney

UNITED STATES PATENT OFFICE.

THOMAS S. KNOTTS, OF LITTLE ROCK, ARKANSAS.

CONVERTIBLE HAT.

1,347,338.

Specification of Letters Patent. Patented July 20, 1920.

Application filed July 28, 1919. Serial No. 313,688.

To all whom it may concern:

Be it known that I, THOMAS S. KNOTTS, a citizen of the United States, residing at Little Rock, in the county of Pulaski, State 5 of Arkansas, have invented certain new and useful Improvements in Convertible Hats, of which the following is a specification.

My invention relates to hats and particularly to an improved construction for controlling the ventilation of the hat to meet the requirements of climatic changes.

It is my purpose to provide an improved construction of the character named which 5 will be exceedingly simple, efficient in use, and which can be incorporated in a hat or cap structure without materially increasing the expense of production.

It is also my purpose to provide a construction for controlling the ventilation of hats which can be easily manipulated by the wearer and which will be positively controlled in either a ventilating or non-ventilating status.

With the above and other purposes in view my invention consists in the details of construction and in the arrangement and combination of parts to be hereinafter more fully described and particularly 5 pointed out in the appended claims.

In describing my invention in detail reference will be had to the accompanying drawing wherein like characters of reference denote corresponding parts in the several views and in which—

Figure 1 is a side view of a cap embodying my invention and shown partly in elevation and partly in section, the ventilating structure being in open position;

Fig. 2, a fragment of what is shown in Fig. 1 with the ventilating structure in closed position;

Fig. 3, a section on the line 3—3 of Fig. 1; and

Fig. 4, a section on the line 4—4 of Fig. 2.

Referring to the drawings A indicates generally a military cap the crown of which is formed of foraminous material B, preferably woven wire cloth, which is pressed to the desired shape and provided with a suitable covering 10 on its top and

the upper portion of its side, while a corresponding covering 11 is provided around the lower portion of its side. The covers 10 and 11 have their adjacent edges spaced 55 so as to leave a portion 12 of the foraminous material exposed to provide the necessary ventilating openings. The crown is provided interiorly with the usual sweat band 13. Movable longitudinally between the 60 crown and the sweat band 13 is an annular shutter 14 which is normally held in uncovering relation to the exposed portion 12 of the foraminous material by means of elastics 15 which are secured at their lower 65 ends to the crown and at their upper ends to the shutter 14. When the shutter 14 is moved into covering relation with respect to the exposed portion 12 of the foraminous material the elastics 15 are tensioned and 70 the shutter is held under such conditions by coöperating fastening devices 15' and 16 on the shutter and crown respectively. It will be obvious that when the shutter is in the position shown in Fig. 3 the desired ventilation can be had through the exposed 75 portion of the foraminous material, while movement of the shutter to the position shown in Fig. 4 will prevent circulation of air in a manner through the exposed foraminous material 12. 80

While I have described one particular form of carrying my invention into practice it will be obvious that various changes in the details of construction may be resorted to without departing from the scope 85 of the appended claims.

What I claim is:—

1. In a hat, a crown portion having openings in the side thereof, a shutter movable 90 longitudinally with respect to the crown to cover and uncover said openings, means constantly tending to hold said shutter out of covering relation to the openings, and means for positively and detachably securing the shutter in covering relation to said openings. 95

2. In a hat, a crown portion having openings in the side thereof, a shutter movable longitudinally with respect to the crown to 100 cover and uncover said openings, elastic elements secured to the crown and shutter

for holding said shutter normally out of covering relation to the openings, and co-operating fastening devices on the shutter and crown for positively and detachably holding the shutter in covering relation to said openings against the influence of said elastic members.

In testimony whereof I hereunto affix my signature in the presence of two witnesses.

THOMAS S. KNOTTS.

Witnesses:

EDW. B. RUNIE,

WALTER J. TERRY.
